United States Patent Office.

C. ALBERT WIGGIN, OF NORTH SANDWICH, NEW HAMPSHIRE.

Letters Patent No. 80,580, dated August 4, 1868.

IMPROVED APPLE-PARER.

The Schedule referred to in these Letters Patent and making part of the same.

TO ALL WHOM IT MAY CONCERN:

Be it known that I, C. ALBERT WIGGIN, of North Sandwich, in the county of Carroll, and State of New Hampshire, have invented certain new and useful Improvements in Apple-Parers; and I do hereby declare that the following is a full, clear, and exact description thereof, reference being had to the accompanying drawings, and to the letters of reference marked thereon, which form a part of this specification, in which—

Figure 1 represents a perspective view, and

Figure 2 a side elevation of my apple-parer.

Figure 3 is a plan view of the platform upon which the knife-table revolves, with the gearing for operating the table attached.

Figure 4 represents an under side view of the table, and

Figure 5 a side view of the pinion which gears with the table.

The nature of my invention consists in constructing about one-half of the under side of the outer edge of the circular revolving table upon which the knife is situated with a cogged surface, into which gears a pinion, with a portion of its cogs cut away, so that when the knife has travelled its required circuit, the table will immediately return to its original position, substantially as hereinafter set forth.

My invention consists, further, in such other devices as will be hereinafter described.

To enable others to employ my invention, I will now describe its construction and operation.

In the accompanying drawings, A represents a frame, made as seen in figs. 1 and 2, and provided at its lower end with a clamp, by means of which it is secured in position.

On the outer end, a, of frame A, is permanently secured a semicircular platform, C; shown in fig. 3, which is provided or formed with a projection, e, projecting beyond the end of a, and fitting against a projection, b, formed on the lower side of the revolving table, B, the object of which will be seen hereafter.

B designates the circular revolving table, which is placed upon the vertical shaft b¹, working in the end, a, of frame A. About one-half of the outer edge of the under side of the table B is cogged.

Between the point where the cogs on table B terminate, and the projection b, the table is furnished or formed with a recess, b².

D represents a rubber or elastic spring wound around the shaft b¹, and secured at its lower end to a bar of frame A, and by means of which the table, when disengaged from its pinion, is forced back to its original position.

F is a pinion gearing with the cogs on table B, and working on a horizontal shaft, f. The pinion F has a portion of its cogs cut away, so that when the knife is directly in front of the fork upon which the apple is placed, or the knife has accomplished its required circuit, the point on the pinion F where the cogs are removed will come in contact with the recess b² on table B, and thus allow the table to be relieved from the pinion, and cause it to be forced back to its first position by the spring D.

G designates the knife, provided with the handle g, which is secured to a rocking-shaft, g³, supplied with a spring, g¹, and pivoted in ears secured to the top of the table. This shank or handle g is also provided with a spring, g², near its centre, and at right angles with the spring g¹.

J is the apple-fork, which has a revolving motion through a pinion, j, placed on a shaft, j', fastened to said fork. The pinion j gears with a pinion, h, which is provided with another pinion, h', gearing into the main gear-wheel L, which is situated upon the outer end of shaft f of pinion F.

I designates the handle, which is attached to gear-wheel L.

An advantage which I claim in the construction of my apple-parer is, that it cannot be clogged by the parings from the apple, as the table acts as a shield to the gearing, it being situated on the lower side of the table, as already explained.

What I claim as new, and desire to secure by Letters Patent, is—

1. The turn-table B, cogged as described, and furnished with projection b, in combination with pinion F, constructed and arranged to operate substantially as set forth.

2. Shaft b¹, spring D, pinion F, table B, shank g, knife G, springs g¹ and g², fork J, shaft j', pinions j, h, and h', gear-wheel L, and shaft f, all combined and arranged substantially as and for the purpose set forth.

In testimony that I claim the foregoing as my own, I affix my signature in presence of two witnesses.

C. ALBERT WIGGIN.
